Primary Examiner — Andrew Kerr(74) *Attorney, Agent, or Firm* — Michael Best & Friedrich LLP(57) **CLAIM**

The ornamental design for a bottle, as shown and described.

DESCRIPTION

FIG. 1 is a top perspective view of a bottle, showing our new design.

FIG. 2 is a bottom perspective view of the bottle shown in FIG. 1.

FIG. 3 is a left side view of the bottle shown in FIG. 1; and, FIG. 4 is a right side view of the bottle shown in FIG. 1. The dash-dash broken lines represent portions of the article that form no part of the claimed design. The dash-dot broken lines represent boundaries of the claimed design and form no part of the claimed design.

1 Claim, 3 Drawing Sheets
